United States Patent Office

Des. 212,346
Patented Oct. 1, 1968

212,346

DISPLAY STAND

David P. Shea, Chagrin Falls, Ohio, assignor to Crawford Fitting Company, Solon, Ohio, a corporation of Ohio

Original design application Feb. 8, 1967, Ser. No. 5,731.
Divided and this application Dec. 29, 1967, Ser. No. 9,996

Term of patent 14 years

(Cl. D80—9)

FIG. 1

FIG. 2

FIG. 4

FIG. 1 is a front perspective view of a display stand embodying my new design;

FIG. 2 is a side elevational view thereof;

FIG. 3 is a top plan view thereof; and

FIG. 4 is a bottom plan view thereof.

The rear elevation of the display stand is plain and unornamented.

This is a division of design application Ser. No. D. 5,731, filed Feb. 8, 1967, now abandoned.

I claim:

The ornamental design for a display stand, substantially as shown and described.
